(57) **CLAIM**

The ornamental design for a toy, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top, front, left side perspective view of a toy, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a perspective view thereof, shown in a state that a front part of a house of the toy is opened.

FIG. 9 is a front elevation view thereof, shown in a state that the front part of the house of the toy is opened.

FIG. 10 is a rear elevation view thereof, shown in a state that the front part of the house of the toy is opened.

FIG. 11 is a left side elevation view thereof, shown in a state that the front part of the house of the toy is opened.

FIG. 12 is a right side elevation view thereof, shown in a state that the front part of the house of the toy is opened.

FIG. 13 is a top plan view thereof, shown in a state that the front part of the house of the toy is opened; and,

FIG. 14 is a bottom plan view thereof, shown in a state that the front part of the house of the toy is opened.

The areas surrounded by broken line form no part of the claimed design.
